(57) CLAIM

The ornamental design for bath accessory base, as show and described.

DESCRIPTION

FIG. 1 is a top, front, and left side perspective view of a bath accessory base showing my new design;

FIG. 2 is a left side elevational view thereof;

FIG. 3 is a right side elevational view thereof;

FIG. 4 is a rear elevational view thereof,

FIG. 5 is a front elevational view thereof;

FIG. 6 is a top plan view thereof;

FIG. 7 is a bottom plan view thereof;

FIG. 8 is a top, front, and left side perspective view thereof, showing a broken-line representation of an alternative mounting environment;

FIG. 10 is a reduced top, front, and left side perspective view thereof, showing a broken-line representation of another alternative mounting environment; and,
